UNITED STATES PATENT OFFICE.

JAMES VICTOR THOMAS EAST, OF SPRINGFIELD, MASSACHUSETTS, ASSIGNOR TO
A. G. SPALDING & BROS., OF NEW YORK, N. Y., A CORPORATION OF NEW JERSEY.

GOLF-CLUB HEAD.

Application filed May 4, 1926. Serial No. 106,701.

The invention relates to a golf club embodying improvements on the form shown in my Patent #1,571,109, issued Jan. 26, 1926.

- 5 The improvements comprise the insertion of a sealing sheet of pyroxylin or like material between the sole plate and the head, which sheet has a homogeneous union with the impact member.
- 10 The invention consists in the features and combination and arrangement of parts hereinafter described and particularly pointed out in the claims.

Figure 1 is a transverse sectional view of the golf club head with the insert in place, and with the sealing sheet disposed between the sole plate and the head and impact receiving insert.

15 Fig. 2 is a longitudinal sectional view of the club head.

Fig. 3 is a front view of the club head embodying the invention.

20 In the drawings, 1 indicates the club head having a recess 2 in which the impact receiving insert 3 is to be located. The recess 2 has upwardly converging walls which are in alignment with and engageable by the walls of the insert 3, when inserted.

25 Insert 3 comprises a foundation member 3^a of pyroxylin or like material which is secured to the club head by screws 3^b and a facing piece 3^c of the same material as the member 3^a and having a homogeneous union therewith.

30 A recess 4 is formed in the bottom of the club head for receiving the sole plate 5. A sealing sheet 6 is interposed between the sole plate and the bottom of the recess 4, covering the same and having an edge portion 7 contacting with the insert 3 and flush with the face thereof. The sealing sheet and insert are preferably of the same material, i. e. pyroxylin or the like, whereby the two readily may be united to form a homogeneous union at their surface of contact.

35 In applying the sealing sheet 6, the bottom of the recess 4 is coated with cement. The edge portion 7 of the sheet 6 and the corresponding edge portion 8 of the insert 3 are then softened by the application of a suitable solvent which renders them tacky or sticky so that upon application of the sheet 6 to the recess 4, they readily may be

united to form, when dried, a homogeneous mass. When the union of the sealing sheet 55 and insert and the cement between the sealing sheet and head are thoroughly dry, the sole plate is applied to the bottom of the sealing sheet and suitable fastening means 9 are employed to fasten the sole plate to the 60 head.

The sealing sheet 6 prevents the entry of moisture between the club head or insert and the sole plate and thus overcomes a material difficulty, since the entry of water between the sole plate and club head is a common occurrence and causes warping of the wood and consequent distortion of the parts.

The provision of a sole plate in connection with the impact receiving insert effectively 70 retains the insert in position and protects the lower edge of the insert from injury.

While the sealing insert has been described in connection with the impact receiving insert of the form shown in my Patent 75 #1,571,109, it will be understood that it may be used in connection with other forms of impact receiving inserts.

I claim:

1. In combination, a golf club head, an 80 impact receiving member mounted in said head, a sole plate on said head and a sealing sheet interposed between the sole plate and the head and having a homogeneous union with the impact receiving member. 85

2. In combination in a golf club, a head, and impact receiving member of pyroxylin or like material, a sole plate, and a sheet member of similar material to the impact receiving member interposed between the 90 sole plate and the head and covering the whole area of contact between the sole plate and club head, said sheet member having a homogeneous union with the impact member. 95

3. A golf club head having a recess in the bottom thereof and a recess in the impact receiving face thereof, an impact receiving member in the recess of the face, a sole plate in the bottom recess and a sheet of material interposed between the sole plate and the head, and having a water tight union with the impact receiving member. 100

In testimony whereof, I affix my signature.

JAMES VICTOR THOMAS EAST.
